Specification for Design.

Patented Feb. 4, 1919.

Application filed June 7, 1915. Serial No. 32,755. Term of patent 14 years.

To all whom it may concern:

Be it known that we, OLAF CARLSON and HUGO PICK, both citizens of the United States, residing at Chicago, in the county of Cook and State of Illinois, have invented a new, original, and ornamental Design for Billiard-Cues, of which the following is a specification, reference being had to the accompanying drawing, forming a part thereof.

In the drawing: Figure 1 is a perspective of a billiard cue, showing the new design. Fig. 2 is a perspective of a portion of the handle.

The new billiard cue is characterized in having a checker-board design *a* upon the handle thereof.

We claim:

The ornamental design for a billiard cue, as shown and described.

OLAF CARLSON.
